UNITED STATES PATENT OFFICE.

ELIZABETH ANDERSON DAVIS, OF NEW YORK, N. Y., ASSIGNOR TO BLANCK & COMPANY, INC., OF NEW YORK, N. Y., A CORPORATION OF NEW YORK.

DESIGN FOR EMBROIDERY.

Application filed September 9, 1922. Serial No. 3,666. Term of patent 3½ years.

To all whom it may concern:

Be it known that I, ELIZABETH A. DAVIS, a citizen of the United States, residing at New York, in the county of New York and State of New York, have invented a certain new, original, and ornamental Design for Embroidery, of which the following is a specification.

Said design consists in an embroidered pattern, as illustrated in the accompanying drawing, wherein the figure is a portion of a piece of embroidered lace showing my new design. The design repeats indefinitely on the foundation material in accordance with the length of the piece of embroidery.

What I claim as new is:

The ornamental design for embroidery as herein shown and described.

In witness whereof, I have hereunto set my hand and seal at New York, New York, this 8th day of September, A. D. nineteen hundred and twenty-two.
